HAIR CLIPPER CLEANING AND STERILIZING DEVICE

Edmund J. Loefller, Glendale, Calif.

Application June 1, 1954, Serial No. 433,621

13 Claims. (Cl. 15—4)

This invention relates to a device for cleaning and sterilizing the type of electric hair clipper used in the average barber shop.

A barber shop requirement in most localities is to clean and sterilize the electric hair clipper each time it has been used. But partly because the barber often cannot find time to do this work thoroughly by hand, and also due to carelessness or forgetfulness on the part of some barber, the clipper is often laid aside uncleansed.

It is, in view of the foregoing, the object of the present invention to provide a simple and convenient power driven device which will completely cleanse and sterilize an electric hair clipper. It is a further object to provide a device so constructed that it is merely required to place the clipper therein and to press a button to start the cleaning operation. Another object is to provide a mechanism which will automatically come to a stop at the end of the cleaning operation. A still further object is to provide a device within which the cleansed clipper may remain enclosed to stay clean and sterilized until again needed.

These and other objects of the invention, as well as the many advantageous features thereof, will appear from the following detailed description and by referring to the appended drawings in which a preferred form of the invention is illustrated.

In the drawings:

Fig. 1 is a side elevational view of a device embodying the invention with the side wall of the casing thereof broken away;

Fig. 2 is a substantially corresponding cross sectional end view of the device taken on line 2—2 of Fig. 1; and

Figs. 3—6 are fragmentary views of various portions of the mechanisms within the casing of the device.

The device of the invention is in the drawings shown enclosed within a casing 1, on the floor 2 of which are mounted posts 3, 4 and a bar or rail 5 rises from the floor to support a platform 7 for horizontal sliding movement thereon. The platform is fitted with lugs 8, 9 and these lugs are perforated slidably to seat on a guide rod 10 of the posts 3, 4. A rectangular frame 15 rises from the platform rotatably to support horizontally directed shafts 16, 17 in parallel relation to the guide rod 10 and to each other. Brushes 18, 19 are rigidly secured to the ends of these shafts. A bracket 20 extends horizontally from the end wall 21 of the casing in parallel relation to the two shafts on an axis through the center of the space between the shafts. From this bracket rise rods 22, 23 to form a cradle into which the clipper A is lowered for cleaning and sterilizing purposes, as will now be described. A soft pad 24 may be placed in this cradle for the protection of the cutting edge of the clipper.

An electric motor 30 is shown mounted on the frame 15 and a gear pinion 31 is secured to the motor shaft and acts through speed reducing gears 32, 33 to rotate gears 34, 35 of the brush shafts 16, 17. This entire brush assembly is advanced to move the brushes across the cradled lower end of the clipper in the following manner. A stub shaft 36 is vertically seated for rotation in brackets 37, 38 extending from the frame 15 and a worm gear 39 of this shaft is in mesh with a worm 40 of the shaft 16. A bar 45 is at 46 shown pivotally

2

secured in position on the post 4 and an arm 47 of the stub shaft 36 is pivotally connected to the end of this bar. When so connected, it is found that rotation of the shafts 16, 17 by the motor will impart rotation to the stub shaft 36 thereby to turn the arm 47 in a circle to advance the brush assembly on the guide rod 10 and again to return the assembly to its initial position. The revolving brushes are during this advance and return movement caused to sweep over the cutting surfaces of the clipper head thoroughly to dislodge any hair or other matter adhering thereto. The bar 45 is during this assembly movement free to oscillate on its pivot 46 to provide space for this turning movement of the arm.

Means must be provided to discontinue the movement of the brush assembly upon return to its initial position. This may be done in the following manner. A conventional micro switch 50 is suitably mounted at the top of the casing. This switch is, by conduits 51, 52, cut into the motor circuit and a spring-held push button 53 of the switch is manually depressible to close the motor circuit to start the brush assembly movement. This type of micro switch is usually made with a downwardly projecting plunger 55 and this plunger is, in a manner common in such micro switches, moved downward by the depressed button to maintain the circuit closed. A flat spring 56 is fastened to the bottom of the switch and it extends past the lower end of the plunger 55. A pawl 57 is at 58 shown hung to swing on a bracket 59 of the frame 15 in close proximity to the rear end of the spring 56.

When the push button 53 is depressed to close the circuit to advance the brush assembly, and with it the pawl 57, it is found that the end of the spring will cause the pawl to swing on its pivot to enable the pawl to freely pass under the spring, again to return to its upright position during the continued forward brush assembly movement. But because the pawl by a projection 60 of the bracket 59 is held against oscillating movement in the opposite direction, it is found that the upper end 40 of the pawl will in nearing the end of the return movement of the assembly gradually force the spring 56 upwardly to cause the plunger to rise and in rising to release the push button 53 for upward movement to open the switch.

It was above given as one of the important features of the invention to provide means for sterilizing the cutting head of the clipper and this may be done during the return movement of the brush assembly in the following manner. An arm 70 is in Figs. 4 and 5 shown mounted to swing horizontally on a post 71 and a spring 72 urges counter-clockwise movement of this arm until arrested by a projection 73 of the casing 1. On a pivot 76 of the arm is mounted a bracket 75 which rises therefrom and is along the upper portion thereof fitted with a soft, moisture absorbing fabric pad 77. A spring 78 maintains this bracket yieldingly in the upright position indicated in the drawings. The arm is swung on the post during the return travel of the brush assembly to move the fabric pad of the bracket yieldingly across the cutter surface of the clipper in the following manner. An L-shaped lever 80 is mounted to swing horizontally on a bracket 81 of the frame 15 and it is by a spring 82 held retracted against a stop 83 of the casing 1. The lever terminates at the forward end thereof in a hook 84 which, at the beginning of the advance movement of the brush assembly will pass over the stud 85, in passing to cause the lever to swing on its pivot against the tension of the spring 82 without disturbing the position of the arm 70 and the bracket 75 thereon. But toward the end of the return movement of the brush assembly it is found that the hook will engage the stud 85 to swing the arm and bracket to carry the

fabric pad across the cutting surface of the clipper after the brushes have receded therefrom. The lever will now reach the stop 83 and will be swung on its pivot to clear the stud 85 of the arm 70, attaining the position indicated in Fig. 4 at the end of the brush assembly return movement.

Mechanism is provided for dispensing a measured quantity of disinfecting fluid for deposit on the fabric pad during the return movement of the brushes over the clipper surface. This mechanism may, as best shown in Figs. 5 and 6, include a reservoir 90 to which a valve casing 91 is secured and a valve stem 92 is seated in this casing. An L-shaped passage 93 is cut through the stem for registration with a passage 94 leading from the reservoir to the valve. A rod 95 rises from the valve stem to a position between studs 96, 97 of a bracket 98 which, in turn, extends from the frame 15, substantially as shown in Fig. 1. During the advance movement of the brush assembly it is found that the stud 97 will reach and swing the rod 95 forward, thereby to rotate the valve stem to bring the passage 93 thereof into registration with the passage 94 and with a discharge spout 99 to open a passage for the disinfectant from the reservoir to flow through the spout for deposit on the fabric pad 77. This discharge continues until the stud 96, on the return movement of the brush assembly, returns the rod 95 to its initial position to cut off the supply of sterilizing fluid.

While the brushes and the fluid carrying pad 77 may be depended upon thoroughly to cleanse the lower portion of the clipper, it may be found desirable also to cleanse a portion of the clipper above the cutter surface thereof. This may be done by mounting a bracket 100 on the frame 15 and by seating a soft brush 101 in this bracket. This brush will sweep all hair and other foreign matter away from the electric clipper during the movement of the brush assembly and it may be detached from the assembly when not needed by merely loosening the clamping screw 102. For the sake of clearness only one such brush is illustrated in the drawings but I wish to point out that a similar brush may be placed on the frame at the other side thereof in reverse position to cleanse the opposite side of the clipper.

Once the clipper has been lowered into position in the cradle and the motor started, no further attention is necessary and the clipper may remain in the casing until again needed. During this waiting period, it may be well to provide means for more completely enclosing the clipper partly to prevent dust and other foreign matter from entering the casing and also to retain the full benefit of the sterilizing fumes generated during the cleansing operation. I have for this purpose added a cover 105, which by a hinge 106 is mounted on the top plate of the casing. When this cover is of a size freely to encompass the upper portion of the clipper and fully to enclose the opening 107 through which the clipper is inserted, it is found that the clipper may remain in the casing indefinitely. And when a suitable handle, such as the stud 108 shown in Fig. 2 of the drawings, is provided this cover may be conveniently operated. It will, of course, be necessary to provide an outlet for the clipper conduit B, and this may take the shape of a notch 109 cut into the lower edge of the cover. The hinge 106 of the cover is in the drawing for the sake of simplicity and clearness shown placed lengthwise of the casing nearer the rear wall thereof, but it is to be understood that the cover may be turned right or left to position the hinge transversely on the casing if found more convenient.

While I have herein described a preferred form of the invention, it is to be understood that modification, within the scope of the claims hereto appended, may be embodied to the end that an attractive and conveniently operable device may be produced. It may, for example, be found desirable so to shape and position the brushes and the fabric pad that they will more completely cleanse and sterilize the portion of the clipper within the casing.

I claim:

1. An electric clipper cleaning and sterilizing device comprising, a casing having an opening in its upper surface, a seat in the casing for the cutter head of a clipper to be cleaned directly below said opening, a frame seated for reciprocation in the casing, a pair of shafts mounted for rotation in the frame and extending therefrom toward said seat, brushes on said shafts, a motor connected to rotate the shafts and brushes, connections from the motor to move the frame forward and backward to cause the rotating brushes to sweep across both faces of the cutter head, a starting switch to close the motor circuit, and means engaging the switch on the return movement of the frame to open the circuit.
2. An electric clipper cleaning and sterilizing device comprising, a casing having an opening in its upper surface, a seat in the casing for the cutter head of a clipper to be cleaned directly below said opening, a hinged lid on the casing for closing the opening entirely to enclose the clipper, a frame seated for reciprocation in the casing, a pair of shafts mounted for rotation in the frame and extending therefrom toward said seat, brushes on said shafts, means for moving said brushes forward and back across the clipper head at both sides thereof, a fabric pad actuated by said brush moving means to sweep over the clipper head surface following the return movement of the brushes, a motor for actuating said means, a starting switch for the motor, devices actuated by said brush moving means to open said switch at the end of the brush return movement, and means for applying sterilizing fluid to the pad before passing over the blade surface.
3. An electric clipper cleaning and sterilizing device comprising, a casing having an opening in its upper surface, a seat in the casing for the cutter head of a clipper to be cleaned directly below said opening, a hinged lid on the casing for closing the opening entirely to enclose the clipper, a frame seated for reciprocation in the casing, a pair of shafts mounted for rotation in the frame and extending therefrom toward said seat, brushes on said shafts, means for reciprocating the frame to move said brushes forward and back across the clipper head at both sides thereof, an element extending from the frame, a fabric pad actuated by said element to sweep over the clipper head surface following the return movement of the brushes, a motor for actuating said means, a starting switch for the motor, devices actuated by said brush moving means to open said switch at the end of the brush return movement, a container for sterilizing fluid, a container discharge valve, and an element on said brush moving means engaging said valve to open and close the valve to deposit sterilizing fluid on the fabric pad before its sweep across the cutter blade surface.
4. An electric clipper cleaning and sterilizing device comprising, a casing having an opening in the upper surface thereof, a seat in the casing directly below said opening for receiving the cutter head of a clipper to be cleaned, a frame movable in the casing toward and away from said seat, a pair of shafts mounted in and extending from said frame, brushes on said shafts, means for moving said frame to carry the brushes across the clipper head at both sides thereof, a fabric pad actuated by said frame moving means to pass over the clipper head surface following the return movement of the brushes, a container for sterilizing fluid, a valve for dispensing fluid from the container for deposit on the fabric pad, a rod extending from said valve, a bracket on the frame, and studs on said bracket contacting said rod during movements of the frame to open and again to close said valve before the return movement of the brushes across the clipper blade surface to discharge fluid from the container for deposit on the pad.
5. An electric clipper cleaning and sterilizing device comprising, a casing, a seat in the casing for receiving the cutter head of a clipper to be cleaned, a frame movable in the casing toward and away from said seat, a pair of shafts mounted in and extending from said frame, brushes

on said shafts, an electric motor connected to rotate said shafts and brushes at convenient speed, connections from one of said shafts for moving said frame at slow speed to carry the brushes across the clipper head at both sides thereof, a fabric pad actuated by said frame moving means subsequently to pass over the clipper blade surface, a container for sterilizing fluid, and means actuated by the brush moving means to direct fluid from said container to the fabric pad for deposit on the cutter blade before the pad passes over the surface thereof.

6. An electric clipper cleaning and sterilizing device comprising, a casing having an opening in its upper surface, a seat in the casing for the cutter head of a clipper to be cleaned directly below said opening, a frame seated for reciprocation in the casing, a pair of shafts mounted for rotation in the frame and extending therefrom toward said seat, brushes on said shafts, a motor connected to rotate the shafts and brushes, connections from the motor to move the frame forward and backward to cause the rotating brushes to sweep across both faces of the cutter head, a push button starting switch to close the motor circuit, a plunger projecting from the switch, a flat spring on the switch below said plunger, and a pawl on the frame for flexing said spring at the end of the frame movement to move the plunger thereby to open the switch.

7. An electric clipper cleaning and sterilizing device comprising, a casing having an opening in its upper surface, a seat in the casing for the cutter head of a clipper to be cleaned directly below said opening, a frame seated for reciprocation in the casing, a pair of shafts mounted for rotation in the frame and extending therefrom toward said seat, brushes on said shafts, a motor connected to rotate the shafts and brushes, brackets on the frame, a stub shaft supported by said brackets, gear connections from one of the shafts to rotate the stub shaft at slow speed, an arm on the end of the stub shaft, a bar mounted for oscillation in the casing, a pivot interconnecting the free ends of the arm and bar, rotation of the stub shaft and the arm thereon imparting oscillating movement to the frame to cause the rotating brushes to sweep across both faces of the clipper head, a starting switch to close the motor circuit, and means on the frame engaging the switch at the end of the reciprocating frame movement to open the circuit.

8. An electric clipper cleaning and sterilizing device comprising, a casing, a seat in the casing for receiving the cutter head of a clipper to be cleaned, a frame movable in the casing toward and away from said seat, a pair of shafts mounted in and extending from said frame, brushes on said shafts, means for moving said frame forward and back to carry the brushes across the clipper head at both sides thereof, a spring-held arm mounted for horizontal swinging movement above the floor of the casing, a stud on said arm, a bracket rising therefrom, a fabric pad on the bracket, a lever hung to swing on the frame, said lever having a hook on the free end thereof engaging the stud on the return stroke of the frame and lever to swing the arm and bracket to cause the fabric pad to sweep across the clipper head surface of the clipper and again to release the arm and bracket for return movement by the spring thereof, and means for depositing sterilizing fluid on the pad before it sweeps across the face of the clipper.

9. An electric clipper cleaning and sterilizing device comprising, a casing having an opening in the upper surface thereof, a seat in the casing directly below said opening for receiving the cutter head of the clipper to be cleaned, brushes in the casing, means in the casing for moving said brushes across the head of the clipper at both sides thereof and to return the brushes across the clipper head, a fabric pad actuated by said brush moving means to pass over the clipper head surface following the return movement of the brushes, a container for sterilizing fluid, and means actuated by the brush moving means to direct fluid from said container to the fabric pad for deposit on the clipper head surface as the pad passes over it.

10. An electric clipper cleaning and sterilizing device comprising, a casing having an opening in the upper surface thereof, a seat in the casing directly below said opening for receiving the cutter head of a clipper to be cleaned, a pair of brushes mounted for rotation in the casing, means for rotating and moving said brushes across the clipper head at both sides thereof and to return the brushes across the clipper head, a fabric pad actuated by said brush moving means to pass over the clipper head surface following the return movement of the brushes, a container for sterilizing fluid, and means actuated by the brush moving means to direct fluid from said container to the fabric pad for deposit on the cutter blade surface as the pad passes over the surface.
11. An electric clipper cleaning and sterilizing device comprising, a casing having an opening in the upper surface thereof, a seat in the casing directly below said opening for receiving the cutter head of a clipper to be cleaned, a hinged lid on the casing for closing the opening to enclose the clipper within the casing, a pair of brushes in the casing, means for moving said brushes across the clipper head at both sides thereof and to return the brushes across the clipper head, a fabric pad actuated by said brush moving means to pass over the clipper head surface following the return movement of the brushes, a container for sterilizing fluid, and means actuated by the brush moving means to direct fluid from said container to the fabric pad for deposit on the cutter blade surface as the pad passes over the surface.
12. An electric clipper cleaning and sterilizing device comprising, a casing having an opening in its upper surface for passage of a clipper to be cleaned into the casing, a seat in the casing for the cutter head of the clipper directly below the opening, a hinged lid on the casing for closing the opening entirely to enclose the clipper, a frame seated for reciprocation in the casing, a pair of shafts mounted for rotation in the frame and extending therefrom toward the seat, brushes on said shafts, means for moving said brushes across the clipper head at both sides thereof and to return the brushes across the clipper head, a fabric pad actuated by said brush moving means to follow the return movement of the brushes and to sweep over the clipper head surface, and means for applying sterilizing fluid to the pad before passing over the clipper head surface.
13. An electric clipper cleaning and sterilizing device comprising, a casing having an opening in the upper surface thereof, a seat in the casing directly below said opening for receiving a clipper to be cleaned, an inwardly directed bracket in the casing, rods rising from said bracket to form a cradle for receiving the cutter head of the clipper, a platform movable in the casing toward and away from said seat, means for guiding said platform, a frame on the platform, a pair of shafts mounted in and extending from said frame, brushes on said shafts, means for moving said frame to carry the brushes forward and back across the clipper head at both sides thereof, a fabric pad actuated by said frame moving means to pass over the clipper head surface following the return movement of the brushes, a container for sterilizing fluid, and means actuated by the brush moving means to direct fluid from said container to the fabric pad for deposit on the cutter head before the pad passes over the surface thereof.
